UNITED STATES PATENT OFFICE.

FRANK MANNING, OF PHILADELPHIA, PENNSYLVANIA.

ATTACHMENT FOR TYPE-WRITERS.

973,058.

Specification of Letters Patent. Patented Oct. 18, 1910.

Application filed December 11, 1909. Serial No. 532,712.

To all whom it may concern:

Be it known that I, FRANK MANNING, a citizen of the United States, residing in the city and county of Philadelphia, State of Pennsylvania, have invented a new and useful Attachment for Type-Writers, of which the following is a specification.

My invention relates to a new and useful attachment for typewriters, wherein I provide means for feeding paper to the typewriter with carbon therebetween, whereby an original and one copy of the writing are obtained, said paper being in any suitable form such as sheets or a continuous strip and when the latter is torn off or cut, if it is desired, after the completion of a desired amount of writing.

It further consists of a novel means for supporting the paper.

20 It further consists of a novel means for supporting the carbon.

It further consists of novel means for mounting the attachment in position on a typewriter.

25 It further consists of other novel features of construction, all as will be hereinafter fully set forth.

I have found in the use of typewriters that it is objectionable to handle carbon sheets inasmuch as the same in many cases soil the hands of the operator and thus the paper, and in addition it is necessary to stop the operation of writing in order to insert new sheets of paper when one is completed.

35 My invention is designed to overcome these defects and in the drawings I have shown an embodiment of my invention which I have found operates successfully in practice, but it will be evident that changes 40 may be made in the construction, the arrangement of the parts may be varied and other instrumentalities may be employed which will come within the scope of my invention, and I do not, therefore, desire to be limited, in every instance, to the exact form as herein shown and described but desire to make such changes as may be necessary.

Figure 1 represents a perspective of an 50 attachment to a typewriter embodying my invention. Fig. 2 represents a back elevation thereof. Fig. 3 represents a sectional view showing a portion of the typewriter

upon which the attachment is supported and showing a section of a platen with the paper and carbon around the same. Fig. 4 represents a perspective view of one of the holders which may be employed for retaining the paper in position in the container. Fig. 5 represents an elevation of a support which 60 may be employed in certain cases. Fig. 6 represents a section showing the form of attachment which is employed on a certain style of typewriters. Fig. 7 represents a perspective of a form which may be employed. Fig. 8 represents a vertical sectional view of the device seen in Fig. 7.

Similar numerals of reference indicate corresponding parts in the figures.

Referring to the drawings:—1 designates 70 an attachment for a typewriter having the end pieces 2 and 3 which are provided with means for connection with the carriage of a typewriter, in the present instance by the projections 4 on the lower portions of said 75 ends, which are provided with seats or means for engagement with arms 5 which are situated in the seats of the projection 4 and are in suitable connection with the carriage of the typewriter. Carried by the ends 80 2 and 3 are the supports or containers for the paper and in the construction shown in Figs. 5 and 6 wherein I employ the paper in rolls, these supports are in the form of tubes 6 and 7, the upper of which in the present 85 instance 6, is provided with the slot 8 extending a suitable distance across the said tube and the other of which 7, is provided with the slot 9 extending a suitable distance across the same.

90 At suitable points in the tube 6 I provide the openings 10 adjacent each end of the same, which openings are adapted to receive the arms 11 carried on the adjustably connected bar 12, said arms 11 projecting a 95 suitable distance into the tube 6 in order to engage with the ends of the roll of paper 13, which is inserted in said tube, in order to hold the roll in proper position therein but will allow free rotation thereof. It will 100 be noted that by reason of the different positions of the openings 10 in the tube 6 I am enabled to vary the distance between the arms 11 in order to accommodate different widths of paper as may be necessary. In 105 the tube 7 I provide similar openings 14

adapted to receive arms 15 similar to those before described carried by the adjustable connected bars 16, the operation of these being the same as that before described with respect to the arms 11, said arms 15 holding a roll of paper 17 in the tube 7 but permitting rotation thereof. The ends of these tubes 6 and 7 may be opened or I may provide the same with suitable closures (not shown) the operation of the tubes being the same whether provided with these closures or not. Rotatably and removably mounted in the ends 2 and 3 is a support or container for the carbon, the support for the carbon in all the figures excepting Fig. 6 is shown as a tube 18 which is adapted to receive a roll of carbon paper 19 seen in Fig. 3, said tube 18 having a slot 20 extending suitably across the same and adjacent one end 20 of said tube 18 I provide a flange 21 which bears against the outer wall of the end 3, in the present instance, to properly locate the tube 18 with respect to the said ends.

22 designates a catch, carried by the end 25 3 in the present instance, which is adapted to be moved into or out of engagement with the flange 21 in order to hold the tube 18 in position but will permit rotation thereof, said tube being provided with the handle or 30 knob 23 for ease, of rotating the same. The opposite end of the said tube 18 can be closed or provided with a suitable closure, as desired but the operation of this tube will be the same in either event.

35 Suitably supported in the present instance upon the tube 7 are the rollers 24, in the present instance carried by the journals 25, said rollers being suitably positioned or adapted to engage with the stationary bar 40 or rod 26, shown in Fig. 3, on the typewriter in order to form a bearing or track along which the attachment can move back and forth as the carriage operates, it being understood that 27 designates a bar or rod, 45 see Fig. 3, which forms a portion of the carriage of the typewriter and to which the attachment is connected in order to move therewith.

28 designates a platen of a typewriter 50 which is of the usual construction and supported in the usual manner.

29 designates a strip or bar which in the present instance is carried upon the upper portion of the tube 6 and so situated that 55 it forms a space 30 between it and said tube.

The operation of the parts so far described is as follows: -The rolls of paper 13 and 17 having been inserted in the tubes 6 and 7 and a suitable roll of carbon 19 having been 60 inserted in the tube 18, the end of the paper 13 is projected through the slot 8 in the tube 6 and the carbon is projected through the slot 20 in the tube 18 and is brought into proper position with respect to the 65 paper extending from the roll 13 with the

carbon side of the paper contacting with the paper. The paper from the roll 17 is projected through the slot 9 and is brought into contact with the other side of the carbon and the three are then passed around 70 the platen 28 of the typewriter, as best understood from Fig. 3. The operator can now use the typewriter in the ordinary manner, the writing being received on one of the papers and the copy being received upon 75 the other. As the platen is rotated in the operation of the machine the three papers, that is the paper 13, the paper 17, together with the carbon paper 19 therebetween will be rotated or carried with the platen without any strain upon the same by reason of the fact that the rolls will freely rotate within their tubes or containers and the paper at the same time acts as its own brake to prevent the same from unrolling too 80 much and so being improperly presented to the platen. Upon the completion of the letter or writing the operator removes the same and the paper and the carbon from the platen and by operation of the handle 23 85 the tube 18 is rotated, removing the carbon 18 from between the papers 13 and 17 and winding the same around the exterior of the tube 18 out of the way. The original and copy of the writing are then passed 90 through the opening 30 until the proper point is reached in the paper with respect to the edge of the bar 29 at which time the operator can tear off the two sheets upon 95 which there is writing and the same is thus 100 complete. The two extending portions of the rolls 13 and 17 are then returned to proper position, the carbon is unrolled from the exterior of the tube 18 and again placed between the extending portions of the paper 105 ready for the next operation.

It will be understood that as the carriage of the machine moves back and forth across the same the attachment by reason of its connection therewith, moves backwardly 110 and forwardly, thus always presenting the paper in the proper position to receive the typewriting, the said attachment being supported as previously stated, by reason of the rollers operating and running upon the 115 bar 26 of the typewriter. Should in any instance the typewriter not be provided with a suitable bar 26 it will only be necessary to attach to the machine or to the stand thereof, a bar similar thereto, as shown in Fig. 5, which will accomplish the same purpose as if the bar were a portion of the typewriting machine proper. In this figure I provide the bosses 31 provided with sockets for receiving the arms 32 which 120 carry the bar 33 upon which the rollers 24 rest and move. I further provide set screws 34 whereby the height of the bar 33 may be adjusted as will be evident.

In some styles of typewriters, such as the 130

"Hammond," which is provided with a cage, a receptacle for the paper, I form my attachment in such a manner that the same can be inserted entirely within the cage. 5 This construction I have illustrated in Fig. 6 in which 35 designates the cage 6 and 7 the tubes for containing the rolls of paper 13 and 17. The slots in the tubes are situated at the top of the tubes and I provide 10 a spindle or rod 36 rotatably mounted in the ends carrying the tubes 6 and 7 and around which spindle the carbon 37 is wrapped or supported, said carbon and the paper from the rolls extending upwardly 15 to the platen of the typewriter and the operation of the parts being the same as already described above.

In the form shown in Figs. 7 and 8, my attachment 1 is formed of the end pieces 2 20 and 3 and the supports for the paper are shown as slotted containers 38 and 39 for receiving sheets of paper 40 and 41 said containers being preferably situated at different heights and between them is situated the 25 support in the form of a tube 18 for the roll of carbon 19. The operation of this form is similar to that already described, the sheet of paper from each container projecting therefrom and receiving the carbon therebetween to be passed around the platen 28 as before. When the writing is completed the carbon is rolled around the tube 18 and removed from its position between the paper and the operator places new sheets of paper 35 in position for the next operation.

From the above it will be understood that I have devised a convenient means for writing and making a copy thereof upon a continuous sheet which is contained in suitable 40 receivers or holders and that the carbon will always be properly positioned between the sheets as desired, the effect of which is evident.

I desire to call attention to the fact that, 45 while I have shown and described two containers for the paper, which is inserted therein in the form of a roll, I may in some instances employ one container with a roll and employ a single sheet for the other portion, using a roll for making the copies and employing a single sheet for the originals, which must be supplied at the proper time, or I may do away with the rolls and employ single sheets, passing from supports or 50 containers in order to properly position the same with respect to the extending end of the carbon.

Having thus described my invention, what I claim as new and desire to secure by Letters Patent, is:—

1. In a device of the character stated, a container adapted to receive paper, a second container adapted to receive paper, each container having a slot whereby the paper can 65 pass from said containers and said slots fac-

ing each other, and a rotatable support for a roll of carbon suitably situated whereby the carbon can be passed and seated between the extending portions of the paper from the containers.

2. In a device of the character stated, a container having a slot therein and adapted to receive a roll of paper, an end of which is adapted to pass through said slot, a second container having a slot therein adapted to receive a roll of paper, an end of which is adapted to pass through said slot the slots in said containers facing each other, a rotatable support for a roll of carbon whereby the carbon can be passed and seated between the extending portions of said paper, and said support being adapted to be rotated to remove the carbon from between said extending portions of paper.

3. In a device of the character stated, a container having a slot therein and adapted to receive a roll of paper, an end of which is adapted to be passed through said slot, adjustable means for holding the paper in said container, a second container having a slot 90 therein adapted to receive a roll of paper, an end of which is adapted to extend from said container through said slot, adjustable means for holding said second roll in proper position within said second container, and a 95 rotatable support for a roll of carbon, a portion of which is adapted to be situated between the extending portions of said paper, and said support being adapted to be rotated to remove the carbon from between the 100 papers.

4. In a device of the character stated, a container having a slot therein and adapted to receive a roll of paper, an end of which is adapted to be passed through said slot, adjustable means for maintaining said roll in 105 position in said container, a second container having a slot therein and adapted to receive a roll of paper, an end of which is adapted to be passed through said slot, an 110 adjustable holder for maintaining the roll in position in said second container, a rotatably mounted support for a roll of carbon whereby the carbon may be extended to a position beneath the extending portions of 115 the paper and can move therewith.

5. In a device of the character stated, a container adapted to receive a roll of paper with an end thereof extending therefrom, a second container adapted to receive a roll 120 of paper with an end extending therefrom, adjustable means for holding said rolls in position in the containers, a rotatably mounted support for a roll of carbon whereby a suitable portion of said carbon can be 125 seated between the extending portions of said paper, and means for connecting said containers and support with the carriage of a typewriter, whereby the same are movable therewith.

6. In a device of the character stated, a container adapted to receive a roll of paper with an end thereof extending therefrom, a second container adapted to receive a roll of paper with an end extending therefrom, adjustable means for holding said rolls in position in the containers, a rotatably mounted support for a roll of carbon whereby a suitable portion of said carbon can be seated between the extending portions of said paper, means for connecting said containers and support with the carriage of a typewriter whereby the same are movable therewith, and a support on which the containers and carbon support move.

7. In a device of the character stated, a container adapted to receive a roll of paper with an end thereof extending therefrom, a second container adapted to receive a roll of paper with an end extending therefrom, adjustable means for holding said rolls in position in the containers, a rotatably mounted support for a roll of carbon, whereby a suitable portion of said carbon can be seated between the extending portions of said paper, means for connecting said containers and support with the carriage of the typewriter whereby the same are movable therewith, and rollers suitably mounted for movement on a suitable support.

8. In a device of the character stated, a container adapted to receive a roll of paper and having a slot therein through which the paper passes as it is unrolled adjustably connected arms passing into said containers for holding said roll in proper position therein, a second container adapted to receive a roll of paper and having a slot therein through which the paper passes, as it is unrolled, adjustably connected arms passing into said second container and adapted to maintain the roll therein in proper position, and a rotatable support for a roll of carbon positioned to permit a suitable portion of said carbon to be situated between the extending portions of said paper.

9. In a device of the character stated, a container adapted to receive a roll of paper and having a slot therein through which the paper passes as it is unrolled, adjustably connected arms passing into said containers for holding said roll in proper position therein, a second container adapted to receive a roll of paper and having a slot therein through which the paper passes as it is unrolled, adjustably connected arms passing into said second container and adapted to maintain the roll therein in proper position, a rotatable support for a roll of carbon positioned to permit a portion of said carbon to be situated between the extending portions of said paper, and means for locking said carbon support in position.

10. In a device of the character stated, end plates, a container stationarily connect-

ed with said end plates and having a slot therein, a second container stationarily connected with said end plates and having a slot therein, a third container removable and rotatably mounted in said end plates and having a slot therein, and a lock for holding said third container in position but permitting rotation thereof.

11. In a device of the character stated, a container having a slot therein and adapted to receive a roll of paper, an end of which is adapted to be passed through said slot, means for holding the paper in said container, a second container having a slot therein adapted to receive a roll of paper, an end of which is adapted to extend from said container through said slot, the slots in said containers facing each other, means for holding said second roll in proper position with said second container, a rotatable support for a roll of carbon, a portion of which is adapted to be situated between the extending portions of said paper and said support being adapted to be rotated to remove the carbon from between the papers, and means for tearing off the ends of the paper containing the writing.

12. In a device of the character stated, means for feeding paper to the typewriter, and a rotatably mounted container having a slot therein and adapted to receive a roll of carbon with an end thereof projecting through the slot, the projecting portion of the carbon being adapted to be seated between said paper and said container adapted to be rotated whereby the extending portion of the carbon will be wrapped around the exterior thereof and so removed from its position between said paper.

13. In a device of the character stated, a container for paper having a slot therein through which an end of the paper is passed, a second container for paper having a slot therein through which an end of the paper is passed, a third container for a roll of carbon having a slot therein through which an end of the carbon is passed and is adapted to be seated between the extending portions of said paper, and means whereby said third container may be rotated so that the carbon is wrapped around the exterior thereof and is removed from its position between the paper.

14. In a device of the character stated, a slotted support for the paper from which said paper is fed, a second slotted support for the paper from which it is fed and a rotatably mounted container for the carbon from which it can be fed, said container being suitably situated whereby the carbon extending therefrom is seated between the paper as it is fed from said supports.

15. In a device of the character stated, a slotted support for the paper from which said paper is fed, a second slotted support

for the paper from which it is fed and a rotatably mounted container for the carbon from which it can be fed, said container being suitably situated whereby the carbon 5 extending therefrom is seated between the paper as it is fed from the said supports, and means for rotating said container where-

by the carbon is removed from between the paper.
